DESIGN FOR A SERVICE BACK BAR COUNTER

Myron E. Steczynski, Chicago, Ill.

Application January 30, 1941, Serial No. 98,562

Term of patent 3½ years

To all whom it may concern:

Be it known that I, Myron E. Steczynski, a citizen of the United States, residing at Chicago, in the county of Cook and State of Illinois, have invented a new, original, and ornamental Design for a Service Back Bar Counter, of which the following is a specification, reference being had to the accompanying drawing, forming a part thereof.

The figure is a perspective view of a service back bar counter, showing my new design.

The dominant feature of my design resides in the portions shown in full lines.

I claim:

The ornamental design for a service back bar counter, as shown and described.

MYRON E. STECZYNSKI.
